UNITED STATES PATENT OFFICE

111,311

DESIGN FOR A MILK BOTTLE

William C. Teunisz, Grand Rapids, Mich.

Application April 8, 1938, Serial No. 76,385

Term of patent 14 years

To all whom it may concern:

Be it known that I, William C. Teunisz, a citizen of the United States, residing at Grand Rapids, in the county of Kent and State of Michigan, have invented a new, original, and ornamental Design for a Milk Bottle, of which the following is a specification, reference being had to the accompanying drawing, forming a part thereof.

The single figure of the drawing is a side elevational view of a milk bottle, showing my new design.

The characteristic features of my design reside

in a bottle as shown, consisting of a cylindrical body having gently rounded shoulders converging inwardly to an elongated neck which flares slightly outwardly and upwardly to a rounded shoulder which curves inwardly to a narrow straight band located between the shoulder and an outwardly rounded rim which curves inwardly to a conventional cap seat.

I claim:

The ornamental design for a milk bottle, as shown and described.

WILLIAM C. TEUNISZ.
